UNITED STATES PATENT OFFICE

ACHILLE KAIS, OF DETROIT, MICHIGAN

OIL BURNER

Application filed October 3, 1927. Serial No. 223,742.

This invention relates to oil burners and more particularly to a novel construction and arrangement of parts tending to simplify, render more efficient, and improve the 5 same generally.

The invention has as one of its primary objects to provide a comprehensive and complete automatically controlled mechanism functioning under every condition and 10 emergency which may arise to fully control the burner. To this end the invention contemplates the provision of mechanism and means operating to shut off the burner irrespective of the operation of the thermostat 15 usually arranged in the room or chamber to be heated. Furthermore, the invention contemplates the provision of means and mechanism for controlling the burner upon the attainment of too great a steam pressure 20 in the boiler; when the water supply in the boiler has fallen below a predetermined amount; or when the oil in the burner has failed to ignite and oil is accumulating owing to the fact that the oil supply has 25 not been shut off.

In addition the apparatus shown and described herein contemplates the provision of means for automatically regulating the supply of air furnished to the burner particularly at each commencement of operation of the burner. This structure likewise provides means for automatically igniting the fuel fed to the burner and for controlling the burner igniting circuit so as to effect 30 an economy in the power which it requires.

While with the structure about to be described the normal control of the burner is automatic and operates in dependence upon the operation of an electrically controlled device, nevertheless this invention 40 contemplates the provision of means for positively mechanically controlling the flow of oil to the burner upon failure of the thermostat; upon the attainment of a predetermined steam pressure; upon the lowering of 45 the water in the boiler or upon an accumulation of oil in the burner.

In addition to the automatically controlled features generally referred to hereinbefore, 50 this invention contemplates novel details of

construction, combinations, and arrangements of parts tending to simplify the construction, cheapen the cost of manufacture and facilitate assembly and upkeep.

The several objects, advantages and novel 55 details of construction of the invention will be made more apparent as this description proceeds, especially when considered in connection with the accompanying drawings wherein:

Figure 1 is a side elevational view of a furnace and an automatic oil burner constructed in accordance with my invention;

Figure 2 is an enlarged fragmentary side elevational view of the main control mechanism illustrated in Figure 1;

Figure 3 is a top plan view of the structure illustrated in Figure 2;

Figure 4 is a fragmentary sectional elevational view taken substantially on the plane 70 indicated by line 4-4 in Figure 3;

Figure 5 is a fragmentary sectional elevational view taken substantially on the plane indicated by line 5-5 in Figure 3;

Figure 6 is a detail sectional view taken 75 substantially on the plane indicated by line 6-6 in Figure 3;

Figure 7 is a vertical sectional view taken substantially on the plane indicated by line 7-7 in Figure 3 showing the safety switch 80 mechanism;

Figure 8 is a detail sectional view taken substantially on the plane indicated by line 8-8 in Figure 3 showing the heating element control switch;

Figure 9 is a fragmentary vertical sectional view taken substantially on the plane indicated by line 9-9 in Figure 3 showing the fuel control valve and the operating 90 mechanism therefor;

Figure 10 is a plan view of the burner showing the ignition element associated therewith;

Figure 11 is a fragmentary sectional view 95 taken substantially on the plane indicated by line 11-11 in Figure 10;

Figure 12 is a fragmentary detail sectional view taken substantially on the plane indicated by line 12-12 in Figure 3 show- 100

ing in detail the connection between the motor and fan housing;

Figure 13 is a detail vertical sectional view taken substantially on the plane indicated by line 13—13 in Figure 1; and

Figure 14 is a diagrammatic view of the wiring circuits.

Referring more particularly to the drawings wherein like reference characters indicated like parts, and more especially to Figure 1, it will be noted that there is illustrated a furnace 15 which may be of any desired type of construction although in the present instance there is illustrated a hot water or steam furnace provided with a water supply pipe 16.

Associated with the furnace 15 is a water level gauge 17 to the upper end of which a T-coupling 18 is connected. To this coupling is connected a flexible hose or tube 19 which communicates with a chamber 20. This chamber is also connected at its lower end by means of a flexible tube or hose 21 with the lower end of the water gauge 17. In this manner chamber 20 is supplied with steam and water and reflects the condition of the water supply and the steam pressure. The bracket 22 secured to the lower leg of the steam water gauge 17 is provided with a bracket arm 23 extending toward the chamber 20 and apertured for slidably engagement with a rod 24 adjustably connected to a lug 25 extending from the chamber 20. Bracket 22 is also provided with an oppositely extending arm 26 on which a lever 27 is pivotally mounted, this lever being provided at one end with an adjustable weight 28 and being pivotally connected as at 29, at its other end, by means of a link 30 to the lever 31. This lever is pivotally mounted as at 32 to a lug 33 projecting upwardly from the cap 34 of chamber 20. Lever 31 is provided with an adjustable weight 35 and movement of this lever is limited in one direction by its engagement with a stop lug 36 also projecting from cap 34, a spring 37 engaging the other end of the lever beyond the pivot point 32 for normally urging lever 31 into engagement with its stop lug 36. Lever 31 is connected by means of a rod 38 to a diaphragm 39 located between the cap 34 and chamber 20. This diaphragm 39 is subject to the steam pressure in chamber 20 and when this steam pressure exceeds a predetermined limit, regulable by adjusting weight 35, lever 31 will be raised and through link 30 will oscillate lever 27 for a purpose to be more fully hereinafter referred to.

Weight 28 on lever 27 acts to counterbalance chamber 20 which is supported by means of the rod 24 and bracket 23 for vertical movement. This chamber is connected by means of a rod or the like 39' to a control lever 40 for a water control valve 41

located in water supply pipe 16. When the supply of water in the boiler of the furnace falls below a predetermined point the amount of water in chamber 20 will be accordingly decreased whereupon weight 28 will predominate, thus permitting chamber 20 to move upwardly, this resulting in an oscillation of lever 27 about its pivot also for a purpose to be more fully hereinafter set forth. This upward movement of chamber 20 opens valve 41 through rod 39' and operates lever 40, thus permitting water to flow into the boiler through water supply pipe 16 until the normal level is reached.

By referring also to Figures 2, 3 and 4 the main burner controlling mechanism will be described. The reference character 42 indicates generally a base or support provided with an upright 43 having secured thereto a sleeve 44 carrying a plate member 45 to which a base plate 46 is secured. This base plate has a portion 47 for supporting a motor 48 and a portion 49 upon which a motor switch 50 is mounted.

A fan housing 51 is secured to the motor 48 in a manner which is most clearly seen from Figures 3 and 12. The fan housing is divided longitudinally providing two half sections fastened together by securing bolts 52, one of these sections being provided with studs 53 projecting from one wall thereof. These studs 53 register with the embossed portions 54 of the motor through which the usual bolts for securing in place the motor casing pass. Two of the studs 53 indicated particularly by the reference character 53^a are recessed as at 55 to receive the heads 56 of the motor casing securing bolts. The other two motor casing securing bolts are removed and the corresponding studs 53 indicated by the reference character 53^b are made of tubular formation to receive bolts 57 passed therethrough from the inside of the fan housing, the ends of these bolts 53 being internally threaded for engagement with the usual threaded studs 58 which normally the securing bolts 56 engage. The heads of the bolts 57 are countersunk so as not to interfere with the rotation of the fan within the fan housing. By this construction simple but satisfactory means is provided for mounting the fan housing 51 upon the motor. It will be obvious that the motor shaft extends into the fan housing for rotating the customary impeller blades or fan.

The motor switch 50 has a shaft 59 upon which several controlling cams are mounted. By reference more particularly to Figures 3, 4 and 5 it will be noted that these cams comprise a main control cam 60 and an ignition circuit control cam 61. Cam member 61 is provided with an eccentrically arranged pin 62 working in a slot 63 of a lever 64. This lever is formed in two parts, one part 65 of which is adjustably connected to the

main part 64, the lever being connected to a shutter 66 pivotally mounted upon the fan casing as at 67. This shutter controls the air inlet of the fan housing 51 and when in closed position permits only a limited amount of air to be forced through the air supply conduit 68 to the burner, yet to be referred to in detail. The pin and slot 62 and 63 between control cam 61 and lever 64 acts as a lost motion connection which permits a limited movement of the cam 61 before the shutter is operated. Thus when the burner is being ignited at the commencement of its periods of operation the amount of air fed thereto is restricted for a purpose to be more fully hereinafter referred to.

The reference character 69 indicates a fuel supply pipe supported by the sleeve bracket 44, this supply pipe being provided with a horizontal leg 70 which extends substantially parallel to the blower or air conduit 68 and extends in through the furnace door to the burner. A short length of pipe 71 is connected to the fuel supply pipe 70 and located below the same and is provided with a removable end cap 72 whereby this section of pipe 71 may be employed as a sediment trap to receive dirt or other solid matter from the fuel. By providing the removable cap 72 this sediment may be conveniently cleaned out.

Mounted upon the fuel supply pipe 70 and branch pipe 71 is a bracket 73 provided with an arm 74 carrying a bearing sleeve 75. Journaled in the bearing sleeve 75 is a shaft 76 to one end of which a cam lever 77 engageable with cam 60 is attached. Mounted on the other end of shaft 76 is a lever 78. As the cam lever 77 and lever 78 are both keyed to shaft 76 they rock in unison.

Located in fuel supply pipe 70 is a valve indicated generally by the reference character 79. This valve is shown more particularly in detail in Figure 9 and consists essentially of a valve port 80 closed by the end of a valve stem 81 passing upwardly through a sleeve 82 threadedly engaging the externally threaded nipple 83 formed on the casing of the valve 79. The upper end 50 of valve stem 81 passes through a guide disk 84 arranged in sleeve 82 and surrounding the end of valve stem 81 is a spring 85 which bears on the one hand against guide disk 84 and on the other hand against a nut 86 threaded on the end of the valve stem. Spring 85 normally urges valve stem 81 upwardly to open valve port 80.

Secured to the upper end of sleeve 82 is a bracket 87 to which a valve operating lever 88 is pivotally connected. The free end of this lever is apertured and passing therethrough is a rod 89. The end of rod 89 is threaded for the reception of a nut 90 constituting an adjustable abutment whereby downward movement of rod 89 will be

imparted to lever 88. Rod 89 passes through an aperture 91 in the short end of lever 78. A spring 92 is arranged between the lever 78 and an abutment 93 carried on the end of rod 89 so that any movement of lever 78 in excess of that necessary to operate the valve compresses spring 92, thus firmly holding valve 81 in closed position. An adjustable stop in the form of a screw 94 is threaded into a lug 95 carried by sleeve 82, this screw passing through an aperture in lever 88 and being provided with a washer or head 96 whereby the upward movement of lever 88 is limited. It will be obvious that with the herein described structure that when the short end of lever 78 is rocked downwardly as viewed in Figures 2 and 9 valve operating lever 88 will be moved downwardly thus forcing valve member 81 downwardly against the action of spring 85 to close port 80 to cut off the supply of fuel being fed to the burner.

Also carried by bracket 73 is a switch box indicated generally by the reference character 97. One section of this box carries a safety control switch adapted to cooperate with the usual thermostatic switch to close the main circuit for starting the burner and acting further to close a second circuit to stop the operation of the burner irrespective of the operation of the thermostatically controlled switch. The switch housing is provided with three binding posts on one side thereof indicated by the reference characters 98R, 99B and 100W and with a fourth binding post 101R. A spring contact member 102 is connected to binding post 98R and as seen in Figure 7 normally contacts with an extension of binding post 101R. Another spring contact member 103 is connected to binding post 100W. Extending through the casing is an actuating arm 104 usually formed of fibre or some other non-conductor. This operating arm 104 operates through a slot 105 formed in the casing and is carried on a rod 106 slidably mounted in guides 107. Rod 106 is provided with a collar 108 against which the forked end 109 of lever 78 engages. Rod 106 is connected by flexible member such as a chain 110 or the like to the end of lever 27 hereinbefore referred to, this chain passing over such idle pulleys 111 or the like as may be necessary. As also previously pointed out lever 27 is caused, under several varying conditions, to rock about its pivot so as to move its outwardly weighted extending end downwardly and this movement transmitted through the flexible element 110 will cause rod 106 to be moved upwardly. By reason of the engagement of the collar 108 with the forked end 109 of lever 78 any upward movement of rod 106 will cause a downward movement of the short end of this lever to thus close the fuel control valve. The upward movement of

70

80

85

90

100

105

110

115

120

125

130

rod 106 also moves fibre control arm 104 upwardly through its slot 105 to thus move spring contact member 102 from its full line to its dotted line position as seen in Figure 5, or in other words, out of engagement with binding post 101R and into engagement with spring contact element 103 and also in engagement with contact 112 carried by binding post 99B.

10 Another section of the switch casing 97 carries a mercury switch 113 controlling the ignition element circuit. This mercury switch 113 is carried by an arm 114 mounted on a shaft 115 journaled in the switch casing 97, this shaft extending to the outside of this housing and carrying an operating arm 116 engagable with cam 61 hereinbefore referred to. A spring 117 normally urges operating arm 116 into the periphery of cam member 61. This cam disk is provided with recessed portions 118, one of which is larger than the other. When the end of operating arm 116 engages either of these recesses mercury switch 113 has been rocked into a position 20 opposite to that shown in Figure 8 wherein the mercury closes contacts 119. During the rotation of cam disk 61 in the direction of the arrow indicated in Figure 5 the circuit to the ignition element will first be closed for a period equal to the time it takes 25 arm 116 to traverse the larger recess 118 whereupon the switch will be opened as the arm engages the peripheral portion 119' and thereafter the switch will again be closed as 30 the arm traverses the smaller recess 118, but in the latter instance the circuit will be closed for a much shorter period and will subsequently be again opened and remain open as long as the operating arm 116 engages 35 the concentric periphery of the cam disk 61 as shown in Figure 5.

For shutting off the oil supply and operating the safety control switch when oil has accumulated as a result of the failure of the 40 burner to properly ignite I provide the following construction. The reference character 120 indicates a return pipe for conducting the oil accumulated in the burner therefrom. This return pipe empties into a 45 bucket or container 121 supported on the end of an arm 122 pivotally mounted on bracket 73 as at 123. The other end 124 of this arm or lever 122 is weighted and engages the lower end of rod 106. The weighted end of 50 lever 122 is sufficient to counter-balance the weight of container 121 but when oil has accumulated in this container it will overbalance the weighted end 124 and rock this lever about its pivot 123 to thus raise rod 55 106 and also rock lever 78 which in turn actuates the valve control mechanism to close the fuel supply valve. Lever 122 is provided with a lug or projection 125 which 60 normally engages against a stop pin 126 in the normal position of these parts.

While any preferred or acceptable form of burner may be employed I have found that a burner constructed substantially in accordance with the disclosure in my Patent No. 1,598,528 dated August 31, 1926, works 70 with complete satisfaction. In the present instance I have however slightly modified some of the details of the burner shown in my aforesaid patent. In the present construction for instance upon the outer guard 75 ring 127 I mount an inner ring 128 substantially of the form illustrated in Figures 10 and 11 and I provide a refractory lining member 129, the upper surface of which is substantially flush with the upper surface 80 of ring 128. Formed in ring 128 is an annular groove for receiving a ring of refractory material 130 in a circular groove of which I arrange my ignition element 131 which as I have shown consists of a resistance element or coil. The two ends of this ignition element are connected to binding posts 132 connected in circuit with the mercury switch 113 hereinbefore referred to. The resistance element 131 is located below 85 the path of the fuel and air thrown radially outwardly by the fuel and air supply means of the burner. The fuel which is thrown outwardly by centrifugal force by the rotating part of the burner runs back down the 90 inclined surface formed by the refractory member 129 and inner ring 128 and through spaced depressions 133 formed in annular rib 134 and thus into engagement at spaced 95 points with the ignition element 131. Thus 100 this fuel becomes ignited at several points circumferentially of the heater and the complete ignition of the burner in an expeditious manner is assured. Located between the fuel and air ejecting means and the ignition element 131 are a plurality of spaced 105 fuel arresting elements 134a formed preferably of chromium steel wire. These members intercept a portion of the fuel and deposit it upon the ignition element to further 110 insure ignition.

The operation of my improved apparatus 115 will now be described, particular reference being had to Figure 14 which shows diagrammatically the wiring circuits.

As is customary a thermostatically controlled switch 135 is arranged in the room or chamber to be heated and in general a three-wire system is employed, the wires thereof extending through switch 97 to the 120 motor switch 50. This motor switch 50 is of the general type now in commercial use and extensively employed in connection with automatic oil burner systems and the like. As this switch forms no part of my 125 present invention it is not described in detail. However, this switch comprises a mechanism whereby shaft 59 carrying cams 60 and 61 is rotated 180° when one of the circuits thereto is closed and the other 180° 130

when the other circuit thereto is closed. This motor switch is also electrically connected to motor 48 by wires 136 so as to control this motor 48 which operates the blower fan. The circuit also includes an outlet box 137 connected to a source of current and connection is made with this outlet box by means of a plug 138 connected by wires 139 to the motor switch 50.

As first mentioned the circuit from the thermostat 135 is a three-wire system, the wires of which are generally designated by colors, there being an electric wire 140, usually white, connected to terminal 141 on the thermostat and to binding post 100W on the safety control switch 97. This binding post is connected by wire 142 to binding post 143 of motor switch 50. This is the white wire of the system which together with either of the other two wires is adapted to complete a circuit to the motor switch to start or stop the operation of the burner. The red wire 144 is connected to binding post 145 on the thermostat and to binding post 98R on the safety control switch 97. This circuit then passes through spring contact element 102 to binding post 101R and then by wire 146 to binding post 147 on the motor switch. With the safety control switch in the position illustrated in Figure 7 the circuit to the motor switch 50 will be complete when the thermostat has operated to close the circuit between the red and white conduits at the thermostat. Blue wire 148 is connected to the other binding post 149 at the thermostat and to binding post 99B at the safety control switch. A wire 150 extends from binding post 99B to binding post 151 at the motor switch and this blue conduit together with the white closes circuit to the motor switch which causes it to make another one-half revolution which shuts off the oil burner.

If, however, the thermostat through failure to operate or some other condition keeps the "on" circuit closed the safety control switch 97 may function to break the white and red circuit and close the white and blue circuit, thus causing the motor switch 50 to operate to shut off the burner. Under these conditions rod 106 is raised through any one of the instrumentalities hereinbefore referred to this movement of rod 106 raising control arm 104 to thus move spring contact element 102 off of binding post 101R and into engagement with contact element 103 as shown by the lines in Figure 7, and also in engagement with contact 112 carried by binding post 99B. The blue and white circuit is then closed through the safety control switch and the motor switch will operate to cut off the burner.

As previously pointed out, rod 106 may be raised to control motor switch 50 in the manner just described either by the move-

ment of diaphragm 39 resulting from an excess of steam pressure in the boiler; by lowering of the water level in the boiler or by an accumulation of oil in the overflow receptacle 121. An excessive steam pressure causes diaphragm 39 to force rod 38 upwardly to thus rock lever 31 which through link 30 rocks lever 27 which through flexible member 110 raises rod 106. If the supply of water falls below a predetermined point weight 128 will overbalance member 20 and also raise rod 106. In a like manner an accumulation of oil in the overflow receptacle 121 will rock lever 122 and raise end 124 and thus force rod 106 upwardly. Any upward movement of rod 106 will rock lever 78 about its pivot 76 by reason of the engagement of collar 108 with the foked end 109 of the lever. Thus the short end of lever 78 is moved downwardly and through rod 89 and the associated mechanism closes fuel control valve 81.

When the red and white circuit is closed through the thermostat and through the safety control switch motor switch 50 will operate to cause shaft 59 to rotate 180°. This positions the recess in cam 60 under the end of lever 77 and rocks shaft 76 so as to rock lever 78 in a direction in which its short end moves upwardly to open the fuel control valve and its other end moves downwardly. This moves rod 106 downwardly and lowers operating arm 104 so that spring contact member 102 rests on binding post 101R and completes the "on" circuit through the safety control switch 107. At the same time cam 61 is rotated to operate the mercury switch 113 which controls the circuit to the ignition element 131. This mercury switch is connected by wires 152 to binding posts 153. From one of these binding posts a wire 154 connects to binding post 132 of ignition element 131. A wire 155 extends from the other binding post 132 through the casing of the mercury switch and then into the motor switch 50.

When cam 61 is operated the end of lever 116 first comes into engagement with the larger recess 118 and rocks mercury switch so that contacts 119 are closed and the circuit completed to the ignition element. This circuit is maintained closed for a period sufficient to bring the coil to a white or red heat whereupon the arm comes in contact with surface 119' and the circuit is opened. During this time the coil 131 cools slightly but before the same is completely cool the switch is closed again by reason of engagement of the arm 116 with the other recess 118. By opening and closing the circuit to the ignition element a saving in electrical energy is obtained and at the same time the element is kept sufficiently hot to quickly ignite the oil.

At the outset it is not efficient to supply

70

80

85

90

95

100

105

110

115

120

125

130

a large quantity of air to the burner as this air will act to cool the ignition element 131 and prevent the ready ignition of the fuel. Therefore the shutter 66 is maintained closed during the first portion of the rotation of shaft 59 or until such time as the oil has been thoroughly ignited. This is accomplished by the lost motion connection between disk 61 and lever 64, the pin 62 sliding idly in slot 63 during the initial movement of the parts and thereafter acting during the remainder of the 180° rotation of shaft 59 to swing shutter 66 to open position to uncover the air inlet opening in the fan housing 51. Thus during the normal operation of the burner this shutter is in open position and a maximum supply of air is furnished the burner.

When the thermostat subsequently closes the white and blue circuit or when rod 106 is raised by any one of the instrumentalities capable of effecting this operation then the motor switch completes another 180° operation and at the same time opens the circuit to the blower motor 48 which was previously closed. Rotation of shaft 59 moves cam 60 from the position shown in Figure 5 to a position where the lever 77 has moved out of the recess, which movement rocks shaft 76 and lowers the short end of lever 78 to close the fuel supply valve. At the same time cam 61 is rotated and through the lever 64 closes shutter 66. It will be understood that prior to the completion of the rotation of cam disk 61 on the previous operation lever 116 had moved to the concentric surface of this cam member to thus move the mercury switch to the off position illustrated in Figure 8.

It will be immediately apparent to those skilled in this art that while one embodiment of this invention has been described and illustrated herein somewhat in detail that various modifications may be made in many of the essential and all of the non-essential details of this invention without departing from the spirit and scope thereof and to this end reservation is made to make such changes as may come within the purview of the accompanying claims.

What I claim as my invention is:—

1. In an oil burner control system, a thermostat switch, a motor switch, electric circuits including said thermostat and motor switches, an air control shutter, a fuel control valve and an ignition element circuit and means operable by said motor switch for controlling said shutter, valve and ignition element circuit.

2. In an oil burner control system, a thermostat switch, a motor switch having a rotatable shaft, electric circuits including said thermostat and motor switches, an air control shutter, a fuel control valve and a switch controlling an ignition element cir-

cuit and cam and lever means operated by said rotatable shaft for controlling said shutter, valve and ignition element switch.

3. In combination, an oil burner, an automatic electric switch device for controlling the same, an ignition device associated with said burner comprising an electrical resistance element, an electric circuit for supplying current thereto, a switch in said circuit and means operated by said switch device for alternately closing and opening said switch during the active period of said resistance element.

4. In combination, an oil burner, an automatic electric switch device for controlling the same, an ignition device associated with said burner comprising an electrical resistance element, an electric circuit for supplying current thereto, a switch in said circuit and cam and lever means actuated by said switch device for alternately closing and opening said switch during the active period of said resistance element.

5. In combination, an oil burner, an automatic electric switch device for controlling the same, an ignition device associated with said burner comprising an electrical resistance element, an electric circuit for supplying current thereto, a switch in said circuit, cam and lever means actuated by said switch device for controlling said ignition circuit switch, said cam being designed to alternately close and open said switch during active period of said resistance element.

6. The combination with an oil burner, of an ignition element therefor comprising an electrical resistance element, a circuit for supplying electric current thereto, a switch controlling said circuit and means for alternately closing and opening said circuit during the active period of said resistance element.

7. In combination, a boiler, an oil burner, control mechanism therefor, a chamber member, means for slidably mounting said chamber member, a pressure actuated diaphragm in said chamber member, a counter-balancing lever, means connecting said lever to said chamber member and diaphragm, means connecting said control mechanism to said counter-balancing lever and means connecting said chamber member to the steam and water chambers whereby said diaphragm is actuated in accordance with changes in steam pressure and said chamber member moved in accordance with said water level to move said counter-balancing lever in accordance therewith.

8. The combination with a boiler and an oil burner therefor, of control mechanism for said burner, including a movably mounted chamber connected to the water chamber of the boiler, a pressure responsive device within said chamber, a control switch and fuel valve and means connecting said cham-

ber and pressure response device to said control switch and fuel valve for operating the latter in dependence upon the water lever and steam pressure in said boiler.

5 9. The combination with a boiler and an oil burner therefor, of a control mechanism including a movably mounted chamber connected to the water chamber of said boiler, a pressure responsive device within said 10 chamber, means for counter-balancing said chamber including a lever, a second lever connected thereto and operatively connected to said pressure responsive device, a control switch and fuel valve, and means connecting 15 said first mentioned lever to said control switch and fuel valve, for the purpose set forth.

10. In an automatic oil burner construction, the combination with an oil burner, of 20 a motor switch, an ignition control cam operated thereby, an air blower, a shutter for said blower and slotted lever and pin means operatively connecting said cam to said shutter, for the purpose set forth.

25 11. The combination with an oil burner having a motor driven air blower, a motor switch, and electric circuits including said motor switch, of a shutter member for controlling the air delivered by said blower, and 30 a slotted lever and pin means connected to said motor switch whereby said shutter is automatically actuated by said switch.

12. The combination with an oil burner having a motor driven air blower, a motor 35 switch, and electrical circuits including said motor switch, of a shutter member for controlling the air delivered by said blower, and means for controlling the said shutter comprising a lever connected thereto and 40 provided with a slot and a rotatable cam pin associated with said motor switch and engageable with said slot for actuating said shutter during a portion of the rotation thereof.

45 In testimony whereof I affix my signature.
ACHILLE KAIS.
